UNITED STATES PATENT OFFICE.

HORACE E. WHITE, OF BALTIMORE, MARYLAND.

SHUTTLE GUARD.

Application filed September 25, 1922. Serial No. 590,443.

To all whom it may concern:

Be it known that I, HORACE E. WHITE, a citizen of the United States, residing at Baltimore, in the city of Baltimore and

5 State of Maryland, have invented certain new and useful Improvements in Shuttle Guards, of which the following is a specification.

10 My said invention relates to a shuttle guard for looms and it is an object of the invention to provide a sectional shuttle guard which is adapted to be used with looms of various widths.

15 A further object of the invention is to provide a shuttle guard which will automatically assume its working position when the loom is started and which will securely lock itself in such position until displaced by the operative.

20 Still other objects are to provide a guard which is adjustable and the end sections of which can be moved out of the way when temples are used on cloth.

25 Referring to the accompanying drawings which are made a part hereof and on which similar reference characters indicate similar parts.

Figure 1 is a plan of my device,

Figure 2 a front elevation,

30 Figure 3 a fragmentary front elevation on an enlarged scale, and

Figure 4 a section on line 4—4 of Figure 1.

35 In the drawings reference character 10 indicates a lay having the usual shuttle race 11, hand cap 12 and reed 13 extending between the race and the cap. A conventional shuttle is indicated at 15 in Figure 4 and this figure also shows the position of the guard relative to the shuttle and other parts.

40 At the front side of the hand cap or reed cap I provide a plurality of plates 16, each of these plates being here shown as held in place by a pair of screws 17 and a bolt 18 extending through the reed cap. Each plate 45 has a vertical slot in which is located a bolt 19 having its head located in a recess in the reed cap back of the plate 16, the recess and the slot both running to the bottom of the cap. This bolt serves to support in position

50 for vertical adjustment a bracket 20 and two or more brackets are provided for each of the rods 21 which are fixed thereto by set-screws 21'. In the present embodiment of the invention I have shown three such rods 55 arranged in line across the front of the reed cap, each rod having two or more sleeves 22

arranged to slide and swing thereon. Each of the sleeves is integral with a guard 23 or 24. It will be seen that the guards 23 at the ends of the lay are relatively short and have 60 but two sleeves whereas the guard 24 may extend substantially across the lay and has several sleeves to carry it. Guard 24 is preferably made in a single section, but may be in several independent sections. 65

Each sleeve 22 has at one end a clutch formation best shown in Figure 1 and comprising a high part 25 and a low part 26 cooperating with a corresponding high part 27 and low part 28 on the adjacent bracket 20. 70 In Figure 1 the guard is shown in operative position with the clutch teeth engaged, this position being also indicated in Figure 4 in full lines. By moving the guard to the left the clutch may be disengaged and by then 75 raising the guard it may be placed in the inoperative position indicated in dotted lines in Figure 4. The endwise movement of the guard is resisted by one or more springs 29 each resting at one end against a collar 30 80 fastened to the rod by a setscrew 30' and serving to maintain the clutch in engagement under ordinary conditions. In the preferred form of my invention these springs 85 are compression springs and their only function is to force the clutch-faces together.

It will be evident that one or more sections of the guard can readily be raised to observe the warp or repair breaks in it while the other sections will remain in operative position. If the operator should neglect to restore any section to operative position it will be thrown down automatically as the lay beats up and when thus thrown down the spring will move it to the right to re-engage the clutch and hold it in place. It may be noted that I may provide clutch teeth on each sleeve 22 as is shown for the middle guard member or on only one of them as on the end members in Figure 1. On wide 90 95 looms three or more sections may be used and preferably one long section and two short sections whereas on narrow ones I preferably use two sections only.

For merely removing the shuttle a single 100 end section only will need to be lifted whereas if it is necessary to work on the warp ends all of the sections may be unlocked and laid back against the top of the hand cap where they will be entirely out of the way. 110 As the guard is stationary in fixed position on the lay while the loom is working it

- will always be in the same position while the shuttles are crossing the loom and can only be lifted after the loom stops. The guard sections can each be adjusted up and down independently by loosening the nuts on bolts 19 and moving the section and its brackets at will. If desired the guard may be lowered to within a fraction of an inch of the cloth or may even touch the cloth.
- 10 When temples are used on the cloth the end sections can be moved up just far enough to clear the temples and the center section may remain in its original position whereby no part of the guard is rendered inactive.
- 15 Preferably the guard extends from the mouth of one shuttle box to the mouth of the other one which leaves no vacant space for the shuttle to get out; at the same time due to the skeleton construction of the
- 20 guard the operative has a clear view of the cloth and the warp ends while the guard is in its working position.

It will be obvious to those skilled in the art that numerous changes can be made in the device as shown in the drawings and described in the specification without departing from the spirit of the invention, therefore I do not limit myself to the specific device illustrated but only as indicated by the appended claims.

Having thus fully described my said invention, what I claim as new and desire to secure by Letters Patent, is:

1. A shuttle guard comprising rods on the lay, guard sections depending from the rods, brackets on the lay having clutch faces adapted to engage with complementary faces on the guard sections to lock them in fixed active position said guard sections be-

ing movable lengthwise of the rods to disengage the clutch teeth and then rotatable thru approximately a half circle into an upper idle position from which they may be dislodged by inertia on the beat-up of the lay, substantially as set forth.

2. A shuttle guard comprising one or more pivoted intermediate sections, independent relatively short guard sections pivoted adjacent each end of the reed cap, means for adjusting the end sections up and down on the lay and means for locking all of the sections in fixed relation to the cap during operation of the loom, substantially as set forth.

3. A shuttle guard comprising one or more intermediate sections, independent guard sections adjacent each end of the reed cap, and means for adjusting the end sections independently up or down on the lay, substantially as set forth.

4. A shuttle guard comprising one or more intermediate sections, and relatively short independent sections pivotally mounted on said cap adjacent the ends thereof whereby said sections may rest loosely against the upper part of the cap in idle position and return to operative position by the beat up of the lay, substantially as set forth.

In witness whereof, I have hereunto set my hand and seal at Baltimore, Maryland this 19th day of September, A. D. nineteen hundred and twenty-two.

HORACE E. WHITE. [L.S.]
